UNITED STATES PATENT OFFICE

LOUIS A. GEBHARD, OF WASHINGTON, DISTRICT OF COLUMBIA, ASSIGNOR, BY MESNE ASSIGNMENTS, TO WIRED RADIO, INC., OF NEW YORK, N. Y., A CORPORATION OF DELAWARE

FILAMENT SUPPLY TRANSFORMER FOR RADIO TRANSMITTERS

Application filed December 3, 1928. Serial No. 323,525.

My invention relates to power supply systems in general and more specifically to power supply systems for energizing thermionic tubes.

An object of my invention is to provide certain improvements in power supply systems for energizing thermionic tubes.

Another object of my invention is to provide a power supply system for thermionic tubes whereby each tube receives the proper amount of energy.

Still another object of my invention is to provide a power supply system for the energization of thermionic tubes whereby the operation or failure of operation of part of the total number of tubes does not affect the supply of proper potential to the remaining tubes.

A general understanding of the power supply system of my invention can be had by referring to the specification to follow and to the accompanying drawing which is a schematic circuit diagram of the power supply system of my invention. The circuit arrangement comprises in combination a master oscillator and power amplifier system employing thermionic tubes 1, 2 and 3 and associated energizing circuits, control circuits and a load or output circuit. In such circuit arrangements, thermionic tubes 1, 2 and 3 usually have different operational characteristics. Thermionic tube 3 is usually of a type having a higher rated wattage output. When such tubes are employed, the rated cathode wattage is usually much greater than that of the tubes having less power output. It is often convenient to energize the respective cathode circuits from a common source of alternating current reduced to the proper operational voltage by means of a step-down transformer. Further, it is often convenient to energize each of the cathode circuits from a common source of alternating current and a common step-down transformer. It has heretofore been the practice to employ separate transformers for energizing the respective cathode circuits, the primaries of which are energized from a common source of alternating current. As an alternative arrangement, transformers have been employed de-

signed to supply the proper energizing potential to the larger thermionic tube and resistances employed connected in series with the tubes of lower rating. Both of the aforementioned means for energizing the cathode circuits of thermionic tubes, have certain disadvantages. In the first instance, the initial cost is increased and the complication of the individual cathode supply wiring circuits are sufficient to warrant improved methods. In the last mentioned system a danger arises that is not present when individual transformers are employed for independently energizing each cathode circuit. When a transformer is employed to energize the larger of a group of thermionic tubes and a resistance is employed in series with each of the cathode circuits of the smaller tubes, the value of the potential in the cathode circuits of the smaller tubes will be largely governed by the characteristics of the cathode circuit of the larger tube. In event the resistance of the cathode circuit of the larger tube is changed the potential supplied to the smaller thermionic tubes will be increased. This rise in potential supplied to the smaller tubes is often sufficient to damage the cathode of the smaller tube, if not entirely destroy it. In the power supply system of my invention the above mentioned difficulties are overcome.

In the accompanying schematic circuit diagram, the cathode circuits of thermionic tubes 1, 2 and 3 are energized by a common source of alternating current reduced to the proper value by transformer 4. Transformer 4 is of the type shell constructed of suitable laminations of thin sheets of iron or silicon steel. Transformer 4 is provided with a magnetic leakage path 9 which constitutes a magnetic leakage path of low reluctance. A primary winding 5 is provided on one side of the transformer core. Opposite the primary winding 5 a secondary winding 7 is provided. On the same side and adjacent to winding 5, a secondary winding 6 is provided. The self-inductance of primary winding 5 is practically constant because of the magnetic leakage path 9 and is little affected by the resistance of winding 7 and associated circuit. Magnetic leakage path 9 prevents ex-

cessive voltage in the associated cathode circuit of thermionic tube 3 during a sudden rise of current in primary winding 5. Fluctuations in the voltage across winding 5 are likewise prevented from materially affecting fluctuations of voltage across winding 6. It is therefore obvious that the energy supplied to thermionic tubes 1 and 2 from transformer winding 6, will be of a substantially constant value. Should the cathode of thermionic tube 3 burn out, excessive potentials will not be supplied to thermionic tubes 1 and 2. Should the cathodes of thermionic tubes 1 and 2 burn out, excessive potentials will not develop in the cathode circuit of thermionic tube 3, due to the comparatively light load of thermionic tubes 1 and 2 and magnetic leakage path 9. Any number of thermionic tubes may be employed with the power supply system of my invention. The power supply system of my invention may be employed for energizing thermionic tubes in a radio receiving set wherein a large number of tubes are employed or in any radio receiving system where it is desired to supply the cathode circuit with a constant potential. It is to be understood that my invention shall not be restricted to the foregoing specification or to the accompanying drawing but only as defined in the appended claims.

What I claim as new and desire to secure by Letters Patent of the United States is as follows:

1. In a system of power distribution for thermionic tubes, the combination of, a transformer having a primary winding connected to an alternating current source and a plurality of secondary windings, said secondary windings being connected to a plurality of thermionic tubes and means to prevent the fluctuations of voltage across one of said windings from materially affecting another of said windings.

2. In a system of power distribution for thermionic tubes, the combination of, a transformer having a primary winding connected to an alternating current source and a plurality of secondary windings, said secondary windings being connected to a plurality of thermionic tubes and means comprising a magnetic leakage path to maintain the induced voltage of said windings substantially constant.

LOUIS A. GEBHARD.
